UNITED STATES PATENT OFFICE.

CHARLES J. EAMES, OF NEW YORK, N. Y.

CREMATION-FURNACE.

SPECIFICATION forming part of Letters Patent No. 331,779, dated December 8, 1885.

Application filed December 9, 1884. Serial No. 149,854. (No model.)

To all whom it may concern:

Be it known that I, CHARLES J. EAMES, a citizen of the United States, residing at New York city, in the State of New York, have invented certain new and useful Improvements in Cremation-Furnaces; and I hereby declare the following to be a clear, full, and exact description of the same, reference being had to the accompanying drawings, in which—

10 Figure 1 is a front elevation showing the end of the retort, the muffle-door, and the induction-pipes for charging the retort with air or oxygen at the close of the process of incineration. Fig. 2 is a vertical longitudinal section on the line $x-x$, Fig. 1. Fig. 3 is a vertical section on the line $y-y$, Fig. 2, showing the flues for the products of combustion, &c., which lead to a suitable stack. Fig. 4 is a view of a fire-brick corpse-bed.

20 Like letters refer to like parts wherever they occur.

My invention relates to the construction of cremation-furnaces, and has for its objects to protect the body during incineration from the direct contact of the flames and products of combustion, so that no extraneous matter may become mingled with the ashes of the subject; to protect the ashes of the subject during the final stages from the drafts and currents of 25 the furnace proper, so that the same may not be disturbed; to provide means for readily handling the corpse when introducing it into the retort, and for withdrawing and securing the ashes thereof, and to provide means for 30 expediting and insuring complete incineration.

To this end it consists in a retort or muffle having perforations in its top, or top and end, above the body-line, said perforations tapering and widest at the outer surface of the retort, so as to maintain more or less pressure in the retort, and in providing a hollowed fire-clay bed or platform for the support of the corpse within the retort and the reception of 35 the ashes.

There are minor novel details of construction which will hereinafter more fully appear.

I will now proceed to describe my invention more fully, so that others skilled in the art to which it appertains may apply the 40 same.

In the drawings, A indicates the outer walls of the furnace, within which, just below the crown or arch A', are longitudinal flues a , communicating by ports a' with the fire-chamber B, surrounding the retort or muffle-chamber. The longitudinal flues a terminate in vertical flues a' , arranged in the rear end wall of the furnace, and these in turn deliver into a common flue, a'' , dotted line, Fig. 3, which 55 leads to a suitable stack.

Within the fire-chamber B, and spanning the same, are suitable arches, b , or equivalent supports for the retort, and below the same is arranged the grate b' , which may terminate 60 in a dead-plate or closed surface, b'' , occupying a space of two or three feet below the front end of the retort or muffle D.

Below the fire-grate b' is the ash-pit b'' , which has its opening at the rear end of the 70 furnace, (or opposite from the retort-door,) and said opening is closed by a detachable or movable door, c , which can be withdrawn to employ the natural draft of the furnace, or closed to employ an artificial draft or blast, 75 for which purpose the door is perforated and provided with a blast-pipe, C.

In the rear wall of the furnace just above the grate-level is a firing and charging door, E, for introducing fuel and kindling the fire 80 in the furnace, and at one or more levels above the same are smaller ports e , each closed by an appropriate stopper, which ports may be employed for feeding in additional fuel when a suitable bed of coals has been established on the grate-bars.

The fuel-doors, stoppers, &c., may be luted up when closed, if desired or found necessary.

D indicates the muffle or retort, which is 90 preferably some nine (9) feet (more or less) in length, of D form, about thirty-six (36) inches wide at the base, and thirty-two (32) inches in height, and perforated upon its upper surface above the body-line, as at d , and also by 95 preference at its end, as at d' . By the term "body-line" as used herein I mean the plane in which the body rests when in the retort. These perforations are preferably tapering or wider at the outer surface of the retort than 100 at the inner, so as to maintain a pressure within the retort, but at the same time permit

the expansion of the gases escaping from the retort, so that they may disperse and mingle with the contents of the fire-chamber and be consumed. I find that a diameter for the holes 5 d d' of one-eighth to one-fourth inch at the inner end, and from an inch to an inch and a half at the outer end serves the purpose intended very well. This retort or muffle is set in the furnace, as hereinbefore specified, with 10 its mouth or open end at the opposite end of the furnace from the firing - doors, and its mouth is closed by a lid or cover, d^2 , provided with a peep-hole, d^3 , through which the interior of the retort can be inspected, and a 15 pipe or port, d^4 , through which air or oxygen can be admitted or forced into the retort toward the close of the incineration process.

F indicates the corpse bed or platform upon which the subject rests. This bed is formed of 20 a slab of fire-clay or other highly refractory material—soapstone or similar substance—which will resist high heats, said slab hollowed upon its upper surface, as at f , and having upon its under surface ball-grooves f' 25 for the reception of refractory balls g .

The construction being substantially of the character before specified, the incineration of the subject will be conducted as follows: A fire being built in the fire-chamber and urged 30 either by the direct draft or a blast until the retort D has reached the proper temperature, the body is placed on the refractory corpse-bed and inserted in the retort, being pushed to the inner or perforated end thereof. The 35 cover of the retort is then applied and luted. The gases, &c., liberated and generated will maintain a limited pressure in the retort D, and, as they gradually escape, will be thoroughly disseminated through the products of 40 combustion being burned therein, and passing with the waste and noxious gases through flues a a^2 a^3 to the stack. Toward the final stage of the process, which altogether will not exceed an hour or an hour and a half duration, 45 air or oxygen may be introduced into the retort through the pipe or port d^4 , which will not only serve to preserve a pressure in the retort and prevent the influx of products of combustion, but will furnish the means of 50 completing the incineration, so that the ashes will be of uniform character and color.

If desired, disinfecting and bleaching gases may be introduced into the retort through the pipe d^4 ; but if there has been a perfect incineration of the body, by the means hereinbefore specified, there will be no need of further treatment. 55

When incineration is completed, the corpse-bed F can be withdrawn without waiting for the retort to cool, as is now practiced, the 60 ashes may be gathered from the hollow bed, and the bed and retort will be ready for the reception of another subject.

I have herein described the retort as set in a furnace using solid fuel; but it is evident 65 that the retort and its adjuncts can be used in conjunction with furnaces employing gaseous fuel and Siemens' regenerator-chambers without departing from the spirit of my invention.

Having thus set forth the nature, operation, 70 and advantages of my invention, what I claim, and desire to secure by Letters Patent, is—

1. The combination, with a furnace or fire-chamber, of a cremation-retort having a series of perforations arranged above the body-line of the retort, which perforations increase in diameter from the inner to the outer surface of the retort, and deliver into the fire-chamber, substantially as and for the purposes 75 specified.

2. A corpse-bed for cremation-retorts, consisting of a refractory slab hollowed out on its upper surface, substantially as specified.

3. A corpse-bed for cremation-retorts, consisting of a refractory slab hollowed on its 85 upper surface, and having ball-grooves on its under surface, substantially as and for the purposes specified.

4. In a cremation-furnace, the combination, with a retort or muffle perforated above the 90 body-line, of a corpse-bed consisting of a refractory slab mounted and movable on refractory ball-rollers, substantially as and for the purposes specified.

In testimony whereof I affix my signature, 95 in presence of two witnesses, this 9th day of December, 1884.

CHARLES J. EAMES.
